UNITED STATES PATENT OFFICE.

JOHN E. CONZELMAN, OF ST. LOUIS, MISSOURI, ASSIGNOR TO UNIT CONSTRUCTION COMPANY, OF ST. LOUIS, MISSOURI, A CORPORATION OF DELAWARE.

COLUMN-SETTING DEVICE.

1,031,049.

Specification of Letters Patent.

Patented July 2, 1912.

Application filed July 13, 1911. Serial No. 638,244.

To all whom it may concern:

Be it known that I, JOHN E. CONZELMAN, a citizen of the United States, residing at the city of St. Louis, State of Missouri, have invented certain new and useful Improvements in Column-Setting Devices, of which the following is a specification.

This invention consists of an improved column-setting device that is particularly adapted to be used for supporting an individually molded concrete column in an upright position in a structure during the erection of a structure, although adapted, of course, for similarly supporting metal columns or other columns.

In the accompanying drawings forming part of this specification, in which like numbers of reference denote like parts wherever they occur, Figure 1 is a top plan view of my column-setting device in conjunction with a concrete column; Fig. 2 is a side elevation of same; Fig. 3 is an end elevation of same; and Fig. 4 is a perspective view of an alternate form of the invention.

The device comprises a pair of timbers 1 between which the column 2 is clamped as hereinafter described. The timbers 1 extend substantially parallel to each other on opposite sides of the column 2 and are preferably connected by a pair of rods 3, one of said rods being located near one face of said column and the other of said rods being located near the opposite face of said column. The rods 3 pass through openings 4 in each timber 1, and are provided with washers 5, both ends of each rod being screw-threaded to receive nuts 6, which, when tightened against the washers 4, draw the timbers 1 toward each other and thereby cause said timbers to clamp the column 2 firmly therebetween. A plurality of openings 4 are provided in each timber 1 for one of the rods 3 and are arranged so that said rod can be inserted through openings either nearer or farther away from the other rod 3 when it is desired to clamp a smaller or a larger column between the timbers 1. If desired, each timber 1 can be provided with a pair of plates 7, said plates being set in depressions in opposite sides of said timber and having openings that register with the plu-

rality of openings 5 for one of the rods 3. By this arrangement, the timbers 1 can be inverted or interchanged when the sides thereof become worn. 55

Each timber 1 is disposed approximately horizontal and is supported at one end thereof on a timber 8 and at the other end thereof on a timber 9, said timbers 8 and 9 being disposed approximately horizontal 60 and extending at substantially a right-angle to each timber 1. A bolt 10, which passes through an opening 11 in timber 1 and, also, through an opening 12 in timber 8, bears a washer 13 and a nut 14 and holds said timber 1 in place on timber 8, there being a plurality of openings 12 in said timber 8. The timber 8 contains a plurality of openings 12 for each bolt 10, so as to allow the timbers 1 to be adjusted for a larger or smaller 70 column 2, and has a pair of plates 15 set in depressions in the upper face thereof and another pair of plates 15 set in depressions in the lower face thereof, each pair of plates being provided with a plurality of openings 75 that register with the openings 12 in said timber. This arrangement allows the timber 8 to be inverted when either the upper or the lower face thereof becomes worn. Each timber 1 is provided with an angle-iron or cleat 16, which is fastened to the inner side thereof by means of a bolt or bolts 17 or other suitable means, said angle-iron being disposed substantially vertical, in order to fit against a face of the column 2. 80 The rods 3 are preferably located nearer the ends of each timber 1 that rest on timber 9 than the ends thereof that rest on timber 8 and one of said rods passes through an opening in said angle-bar 16. A bar 18 is secured to said timber 1 by means of a bolt or bolts 19 or other suitable means and extends through an opening 20 in timber 9, being provided with a washer 21 and having its end screw-threaded to receive a nut 22, 95 which when tightened against the washer 21, draws the timber 9 toward the angle-bars 16 and thereby causes said timber 9 and angle-bars 16 to clamp the column 2 firmly therebetween. A plurality of openings 20 100 are formed in timber 9 for each bar 18 so as to allow the timbers 1 to be adjusted for

a larger or a smaller column. A pair of plates 23 is set in depressions in the face of timber 9, in order to prevent same from becoming worn, and contains a plurality of 5 openings that register with the openings 20 in said timber 9.

After the column 2 has been raised to approximately an upright position by the hoisting machinery or other suitable means 10 (not shown in the drawings), the timbers 1 are clamped firmly against the opposite sides of said column and the angle-bars 16 and timber 9 are clamped firmly against opposite faces of said columns, as hereinabove 15 described. The timbers 1 are clamped against the column 2 at a sufficient distance above the floor or ground 24 to allow a jack-screw 25 to be placed beneath one end of timber 9 and another jack-screw 25 to be placed beneath 20 the other end of said timber 9, and, also, a third jack-screw 25 to be placed beneath approximately the middle part of timber 8. The jack-screws 25 are tightened against the timbers 8 and 9 and are adjusted 25 in the usual manner until the timbers 1 and 9 and angle-bars 16 hold said column in an upright position, after which the hoisting apparatus is released from the column and the timbers 1 and 9 and angle-bars 16 30 hold same in a vertical position. Whenever the base of the column 2 is set in plastic grout or concrete, the timbers 1 can be clamped against the sides of the column and the timber 9 and angle-irons 16 can be 35 clamped against the faces of the column sufficient to support the column in an upright position and, also, to remove the weight of the column from the plastic grout or concrete until after same has set.

40 The column referred to herein may be either an all-concrete column, or may be a reinforced concrete column, or may be either a metal, wood, or stone column, or may be a column in which an ordinary metal column is surrounded by concrete, and said column may, also, be of any size or shape.

It is to be understood that angle-irons, channel-irons, or the like, can be substituted for the timbers 1, 8, and 9, when so desired.

50 In the alternate form of the invention depicted in Fig. 4, the plates 7, 15, and 23 are provided with slots 26, 27, and 28 that register with similar slots in timbers 1, 8, and 9, respectively, in lieu of the spaced openings 4, 12, and 20, so as to allow the rod 3, bolts 10, and bar 18 to be adjusted.

I claim:

1. A column-setting device comprising a pair of members, means connecting said members for clamping same to opposite sides of a column, cleats borne by said members, cross-pieces supporting the ends of said members, and means secured to said mem-

bers for drawing one of said cross-pieces toward said cleats, thereby to clamp the column therebetween. 65

2. A column-setting device comprising a pair of members, means connecting said members for clamping same to opposite sides of a column, cleats borne by said members, 70 cross-pieces supporting the ends of said members, means secured to said members for drawing one of said cross-pieces toward said cleats, thereby to clamp the column therebetween, and means for securing the other of said cross-pieces to said members. 75

3. A column-setting device comprising a pair of members, means connecting said members for clamping same to opposite sides of a column, cleats borne by said members, 80 cross-pieces supporting the ends of said members, means secured to said members for drawing one of said cross-pieces toward said cleats, thereby to clamp the column therebetween, and means for securing the other of said cross-pieces to said members. 85

4. A column-setting device comprising a pair of members, and a pair of rods connecting said members and having means for 90 clamping said members against opposite sides of a column, one of said rods being located near one face of the column and the other of said rods being located near the opposite face of the column, there being a 95 plurality of openings provided in each of said members for one of said rods.

5. A column-setting device comprising a pair of members, a pair of rods connecting said members and having means for clamping said members against opposite sides of a column, one of said rods being located 100 near one face of the column and the other of said rods being located near the opposite face of the column, there being a plurality 105 of openings provided in each of said members for one of said rods, each of said members having depressions in opposite sides thereof, and plates set in said depressions and having openings registering with the 110 openings in said member.

6. A column-setting device comprising a pair of members, means connecting said members for clamping same against opposite sides of a column, and cross-pieces supporting the ends of said members, one of said 115 cross-pieces being relatively longer than the other.

7. A column-setting device comprising a pair of members, means connecting said members for clamping same against opposite sides of a column, cross-pieces supporting the ends of said members, one of said cross-pieces being relatively longer than the other, and bolts securing said members to 125 the short cross-piece.

8. A column-setting device comprising a pair of members, means connecting said members for clamping same against opposite sides of a column, cross-pieces supporting the ends of said members, one of said cross-pieces being relatively longer than the other, and bolts securing said members to the short cross-piece, there being a plurality of openings in the short cross-piece for said bolts. 65
9. A column-setting device comprising a pair of members, means connecting said members for clamping same against opposite sides of a column, cross-pieces supporting the ends of said members, one of said cross-pieces being relatively longer than the other, and bolts securing said members to the short cross-piece, there being a plurality of openings in the short cross-piece for said bolts, said short cross-piece having depressions in the upper and lower faces thereof, and plates set in said depressions and having openings registering with the openings in said short cross-piece. 70
10. A column-setting device comprising a pair of members, means connecting said members for clamping same against opposite sides of a column, cleats borne by said members, cross-pieces supporting the ends of said members, one of said cross-pieces being relatively longer than the other, and a pair of bars secured to said members, said bars extending through openings in the long cross-piece and having means for drawing the long cross-piece toward said cleats, thereby to clamp the column between said long cross-piece and said cleats. 80
11. A column-setting device comprising a pair of members, means connecting said members for clamping same against opposite sides of a column, cleats borne by said members, cross-pieces supporting the ends of said members, one of said cross-pieces being relatively longer than the other, and a pair of bars secured to said members, said bars extending through openings in the long cross-piece and having means for drawing the long cross-piece toward said cleats, thereby to clamp the column between said long cross-piece and said cleats, there being a plurality of openings in said long cross-piece for each of said bars. 85
12. A column-setting device comprising a pair of members, means connecting said members for clamping same against opposite sides of a column, cleats borne by said members, cross-pieces supporting the ends of said members, one of said cross-pieces being relatively longer than the other, a pair of bars secured to said members, said bars extending through openings in the long cross-piece and having means for drawing the long cross-piece toward said cleats, thereby to clamp the column between said long cross-piece and said cleats, and having means in said long cross-piece for registering with the openings in said short cross-piece. 90
13. A column-setting device comprising a pair of members, means connecting said members for clamping same against opposite sides of a column, said members having means for permitting adjustment of said connecting means, cross-pieces supporting the ends of said members, one of said cross-pieces being relatively longer than the other, means connecting said members with the long cross-piece, said long cross-piece having means for permitting adjustment of said last-mentioned connecting means, and bolts securing said members to the short cross-piece, said short cross-piece having means for permitting adjustment of said bolts. 95
14. In a column setting device, a pair of spaced members for engagement on opposite sides of a column, means for clamping said members to said column sides, means in the space between said members to engage a third side of the column, means on the under sides of the said members for engaging a fourth side of the column, and means for drawing said last named means against said fourth side of the column. 100
15. In a column setting device, a pair of spaced members for engagement on opposite sides of a column, means for clamping said members to said column sides, means in the space between said members to engage a third side of the column, means on the under sides of the said members for engaging a fourth side of the column, and means for drawing said last named means against said fourth side of the column, including bars secured to said members and having off-set portions which are threaded at their ends and extend through openings provided therefor in said means for engaging a fourth side of the column, and nuts on said threaded ends of said bars which abut the last named means. 105
16. In a column setting device, a pair of members for engagement on opposite sides of a column, means to draw said members in clamping engagement with the column, means between the members against which a third side of the column abuts, means opposite to and located in a plane beyond that in which said last named means lies to engage a fourth side of the column, and means to draw said means which engages the fourth side of the column into clamping engagement therewith. 110
17. In a column setting device, a pair of members for engagement on opposite sides of a column, means to draw said members in clamping engagement with the column, means between the members against which a third side of the column abuts, means opposite to and located in a plane beyond that in which said last named means lies to engage a fourth side of the column, and means to draw said means which engages the fourth side of the column into clamping engagement therewith. 115
18. In a column setting device, a pair of members for engagement on opposite sides of a column, means to draw said members in clamping engagement with the column, means between the members against which a third side of the column abuts, means opposite to and located in a plane beyond that in which said last named means lies to engage a fourth side of the column, and means to draw said means which engages the fourth side of the column into clamping engagement therewith. 120
19. In a column setting device, a pair of members for engagement on opposite sides of a column, means to draw said members in clamping engagement with the column, means between the members against which a third side of the column abuts, means opposite to and located in a plane beyond that in which said last named means lies to engage a fourth side of the column, and means to draw said means which engages the fourth side of the column into clamping engagement therewith. 125

17. In a column setting device, a pair of longitudinal members for engagement on opposite sides of a column, cross-pieces at opposite ends of said members, and arranged on one of the horizontal faces thereof, means to draw the members together, means between the members to engage a third side of the column, and means connected to each member and to one of the cross-pieces to

draw the latter against a fourth side of the column.

In testimony whereof I have hereunto affixed my signature in the presence of two witnesses.

JOHN E. CONZELMAN.
